UNITED STATES PATENT OFFICE.

ANTHONY K. PETRON, OF AMSTERDAM, NEW YORK.

ARTIFICIAL LIMB.

1,299,504.

Specification of Letters Patent.

Patented Apr. 8, 1919.

Application filed October 4, 1917. Serial No. 194,691.

To all whom it may concern:

Be it known that I, ANTHONY K. PETRON, a citizen of Russia, residing at Amsterdam, in the county of Montgomery and State of New York, have invented certain new and useful Improvements in Artificial Limbs, of which the following is a specification.

This invention relates to certain new and useful improvements in artificial limbs.

10 The primary object of the invention is the provision of an artificial limb in the form of an arm or leg especially adapted for use in the army, the same being easily attached and detached from the person.

15 A still further object of the invention is the provision of an artificial limb having a resilient joint whereby the same is normally outstretched, the limb having a resilient metallic filling giving suitable weight and 20 rigidity to the entire structure, the exterior of the limb being arranged to represent a human member.

25 In the drawings forming a part of this application and in which like designating characters refer to corresponding parts throughout the several views,

Figure 1 is a view of a portion of the frame-work for an artificial leg with parts shown in vertical section.

30 Fig. 2 is a longitudinal sectional view thereof.

Fig. 3 is an elevational view of the complete artificial leg.

Fig. 4 is a detail sectional view of the 35 upper portion thereof.

Fig. 5 is a transverse sectional view of the same.

Fig. 6 is a transverse sectional view taken 40 through the ankle portion of the limb illustrating the foot-frame.

Referring more in detail to the drawing, the limb construction comprises the leg 10 broadly comprising a frame 11 having a foot portion 12 and a thigh portion 13 while 45 a rubber envelop or casing 14 is arranged around the same suitably filled or packed with a metallic hair or fine coiled and tangled wire 15, a belt portion 16 being arranged for securing the leg to the human body by means of lacings 17 with which the belt is arranged.

The leg-frame 11 has opposite upper leg members 18 hinged to opposite lower leg members 19 as at 20 and provided with a 55 connecting spring 21 arranged upon the

pintle 22 of the hinge whereby the upper and lower leg portions are normally maintained outstretched while the lower leg 19 may swing rearwardly only upon the upper leg 18. The foot 12 is hinged as at 23 to 60 the bottom of the lower leg 19 and is provided with a plurality of pivotal toes 24.

A cross-bar 25 is arranged between the upper leg members 18 while a coil spring 26 is arranged around the upper leg members 18 65 and secured thereto by side strips or braces 27, it being understood that the envelop 14 surrounds the entire frame 11 and the spring 26, and is stuffed with the filling 15 to a point adjacent the cross-bar 25. It will 70

also be understood that the spring 26 is closely coiled to form a casing and in the formation of the upper portion of the leg. The closely coiling of the spring 26 gives a neat and natural appearance and prevents collapsing when in use. The filling 15 is also arranged within the upper portion 75

of the leg inwardly of the spring 26 and slightly thereabove adapted for the reception of the stump or portion of the human leg to which the artificial limb is to be connected, the said bar 25 acting as a support for the stump if desired. It will be understood that the foot portion 28 of the leg 80

is of the usual shape of a stocking and encloses the toes 24 within the pointed end portion thereof while a pad 29 is preferably arranged beneath the heel of the foot at the hinged portion 23 thereof extending forwardly beneath the foot as far as the 85 toes 24. With the leg 10 attached to the person in the manner described, the same will perform the functions of an artificial limb.

What I claim as new is:—

1. An artificial limb comprising a frame having upper and lower portions, a spring hinge connection between the said portions, an encircling spring for the upper portion of the frame, an envelop surrounding the 100 frame provided with an attaching portion.

2. An artificial limb comprising a frame having upper and lower portions including spaced parallel members, a spring hinge connection between the pairs of said members, a pivoted brace between the pairs of the upper members of the frame, an encircling spring for the upper portion of the frame and fastening strips secured exteriorly to the upper frame portion over said spring, 105

110

said encircling spring forming a support for the limb.

3. An artificial leg comprising an upper and lower portion having spaced side members, a spring hinge connecting the pairs of the upper and lower portions together, a cross brace secured between the pairs of the upper frame portion, a footing member pivoted between the pairs of the lower frame portion, an encircling spring secured ex-

teriorly to and about the upper frame portion adjacent the connecting member, longitudinally arranged strips secured to the sides of the upper frame portions and against said springs and an attaching means 15 inclosing said frame, said encircling spring forming a support for the attaching means and limb.

In testimony whereof I affix my signature.
ANTHONY K. PETRON.
